UNITED STATES PATENT OFFICE

92,644

DESIGN FOR A COMBINED CASKET LUG AND HANDLE

John E. Burkard, Detroit, Mich., assignor to
Victor Casket Hardware Co., Galesburg, Ill.,
a corporation of Illinois

Application March 29, 1934, Serial No. 51,243

Term of patent 7 years

To whom it may concern:

Be it known that I, JOHN E. BURKARD, a citizen of the United States, and a resident of the city of Detroit, county of Wayne, and State of Michigan, have invented a new, original, and ornamental Design for a Combined Casket Lug and Handle, of which the following is the specification, and reference being had to the accompanying drawing, forming a part thereof.

Figure 1 is a front or face view of the combined casket lug and handle of my invention wherein the handle bar is oval in cross-section.

Figure 2 is an end view of my invention.

I claim:

The ornamental design for a combined casket lug and handle as shown and described.

JOHN E. BURKARD,
